UNITED STATES PATENT OFFICE.

EVALD J. ENGMAN, OF SYRACUSE, NEW YORK, ASSIGNOR TO THE WILL & BAUMER CO., OF SYRACUSE, NEW YORK, A CORPORATION OF NEW YORK.

DESIGN FOR A CANDLE.

51,588.

Specification for Design.

Patented Dec. 18, 1917.

Application filed August 29, 1916. Serial No. 117,543. Term of patent 3½ years.

To all whom it may concern:

Be it known that I, EVALD J. ENGMAN, a citizen of the United States, residing at Syracuse, in the county of Onondaga and State of New York, have invented a new, original, and ornamental Design for a Candle, of which the following is a specification, reference being had to the accompanying drawing, forming a part hereof.

In the drawing, Figures 1 and 2 are respectively top plan and elevation of a candle of my design.

This design for a candle comprises surfaces *a* extending lengthwise of the body of the candle and disposed at an angle to each other, additional surfaces *b* extending

lengthwise of the body of the candle and connecting the surfaces *a*, the surfaces *b* being also disposed at an angle to each other, and lengthwise ribs *c* extending lengthwise of the surfaces *b* and having their bases formed of less width than said surfaces *b* and disposed substantially centrally thereof.

I claim:

The ornamental design for a candle, substantially as shown and described.

In testimony whereof, I have hereunto signed my name, at Syracuse, in the county of Onondaga, and State of New York, this 20th day of June, 1916.

EVALD J. ENGMAN.
